UNITED STATES PATENT OFFICE.

LAWRENCE A. MUELLER, OF KANKAKEE, ILLINOIS, ASSIGNOR TO LEEDY MANUFACTURING CO., OF INDIANAPOLIS, INDIANA, A CORPORATION OF INDIANA.

BASS DRUM AND CYMBAL BEATER.

Application filed May 9, 1921. Serial No. 467,818.

To all whom it may concern:

Be it known that I, LAWRENCE A. MUELLER, a citizen of the United States, residing at Kankakee, in the county of Kankakee and 5 State of Illinois; have invented a new and useful Bass Drum and Cymbal Beater, of which the following is a specification.

It is the object of my invention to provide a combined drum and cymbal beater, operated by the foot, whereby by simply shifting the foot laterally the downward movement of the foot may be made to sound the drum alone or to sound the drum and cymbal together.

15 In the preferred form of my invention I sound both the drum and cymbal when the foot is in normal lateral position, as that is the condition which is desired the greater part of the time, and upon shifting the foot 20 laterally and then pushing down I throw the cymbal-striker out of operation.

The accompanying drawings illustrate my invention. Fig. 1 is a side elevation of a drum and cymbal beater embodying my invention, showing in full lines the parts in normal position, in dotted lines the parts in striking position, and in chain lines the cymbal-striker and its controlling parts in non-striking position; Fig. 2 is a front elevation of the drum and cymbal beater shown in Fig. 1; Fig. 3 is a fragmentary section on the line 3—3 of Fig. 2; Fig. 4 is a section on the line 4—4 of Fig. 1; Fig. 5 is a plan of the drum and cymbal beater shown 35 in Fig. 1, with fragments of the associated drum and cymbal; and Fig. 6 is a side elevation of a modified form of drum and cymbal beater.

The drum and cymbal beater is carried by 40 a frame 10, which lies on the floor and is preferably provided with clamping bars 11, whereby it may be clamped to a hoop of the bass drum. On the operating arm of the frame 10 is pivoted a carrier 12, in which is 45 adjustably mounted the rod 13 which at its outer end carries the drum beater 14. On an arm 15 on the carrier 12 is hung a yoke 16 between which and a cross pin 17 in the bottom of the frame 10 extends an adjustable tension spring 18 which serves the double function of returning the beater to 50 normal position after it has struck and of checking the rebound, the parts 15, 16, and 18 passing from one side of dead center to the other as the device is operated. Such

operation is obtained by a pedal 19 pivoted at its heel end on the horizontal arm 10' of the frame 10 and at its toe end connected by a link 20 to an obliquely upwardly projecting arm 21 on the carrier 12. To get a 60 substantially balanced action, the pedal 19 and the link 20 are bifurcated, as is clear from Fig. 2.

An arm 22 is adjustably attached to the rod 13, by a thumb screw 23, the rod 13 65 being corrugated to facilitate the clamping in different longitudinal and circumferential positions thereon. A rod 24 is pivotally mounted in and extends transversely of the arm 22, and is bent at its free end and provided with a head 25 which forms the cymbal striker. The rod 24 is provided with a crank-arm 26, whereby it may be turned to different positions in the arm 22. This crank-arm 26 is connected to the toe end of 70 a supplemental pedal 27, pivoted at its heel end to one side of the main pedal 19 near the heel end of the latter on a pivot pin 27', and lying beside and roughly parallel to the main pedal 19. When the operator pushes his foot down, he may push down the pedal 19 alone, or both pedals together, depending upon the lateral position to which he shifts his foot. The toe end of the supplemental pedal 27 may be variously connected 75 to the crank-arm 26. As shown in Fig. 6 such connection is by a simple flexible cord 28 which passes from one part to the other through an eye 29 mounted on the frame 10. preferably substantially on the axis about 80 which the carrier 12 moves; a torsion spring 30 acting between the crank-arm 26 and the arm 22 tends to move the rod 24 in a clockwise direction (Fig. 6) to normal position, ready to strike. In the arrangement shown 85 in the remaining figures, a plunger 31 is mounted in a stationary cylinder 32 hung by a finger 33 from the frame 10, which plunger is spring-pressed upward by a compression spring 34 within the cylinder 32. 100 A plunger rod 35 extending downward through the cylinder 32 is attached to a yoke 37 by a removable thumb screw 38, which permits the disconnection of these parts, and a yoke 37 is connected by a link 39 to the toe end of the supplemental pedal 27. The upper end of the plunger 31 is connected by an extensible link to the crank-arm 26. This link is extensible to provide for different 105 adjustments of the arm 22 on the rod 13, and 110

is formed of two telescoping members 40 and 41, clampable together in different relative longitudinal positions by a thumb nut 42, the member 40 being pivoted to the crank-
5 arm 26 and the member 41 having a trans-
verse finger 43 which is releasably attached
by a thumb screw 44 to a yoke 45 carried by
the upper end of the plunger 31.

In operation, when the drummer depresses
10 only the pedal 19, with his foot shifted till
it clears the supplemental pedal 27, the car-
rier 12 is turned to move the parts from full-
line position to dotted-line position (Fig.
15 1), and the drum beater 14 strikes the head
of the drum 50 and the cymbal striker 25
strikes the cymbal 51 which is carried by the
drum, to cause sounding of both drum and
cymbal. However, if the drummer shifts
20 his foot so that it depresses the supplemental
pedal 27 as well as the main pedal 19, the
resultant movement of the cord 28 or of the
plunger 31 and associated parts causes the
25 rod 24 to be turned in the arm 22 as the
carrier 12 is swung toward the striking or
dotted-line position (Fig. 1), so that when
the rod 13 reaches its upper or dotted-line
30 position to make the drum beater 14 strike
the drum head, the cymbal striker 25 has
been moved out of striking position (shown
in dotted lines in Fig. 1) to an inoperative
35 position (shown in chain lines in Fig. 1) so
that such cymbal striker will not strike the
cymbal 51 and such cymbal will remain si-
lent. Thus by depressing only the main
40 pedal, the drummer causes both the drum
and the cymbal to sound; but by depressing
both pedals he causes only the drum to sound
while the cymbal remains silent.

By disconnecting the parts normally con-
40 nected by the thumb nuts 38 and 44, and
withdrawing the horizontal arm 10' of the
frame 10 from cooperation with the rest of
such frame, as I preferably make such two
45 parts separable, it becomes possible to fold
up the drum and cymbal striker into very
small space for transporting and storage.

I claim as my invention:

1. A drum and cymbal beater, comprising
a pivoted arm, a drum beater and a cymbal
50 striker carried by said arm, a pedal for op-

erating said arm to cause the drum beater
to strike a drum head, said cymbal striker
being relatively movable in said arm, and a
supplemental pedal which controls the
55 movements of said cymbal striker in said
arm to determine whether it does or does not
strike the cymbal when said first pedal is
operated.

2. A drum and cymbal beater comprising
a supporting frame, a drum beater and a
cymbal striker movably mounted in said
frame, a main pedal for operating said drum
beater and cymbal striker, and a supple-
60 mental pedal which is so arranged that when it
is depressed with the main pedal it moves
said striker to non-striking position.

3. A drum and cymbal beater, comprising
a pivoted arm carrying a drum beater and
a cymbal striker, a main pedal for operat-
ing said arm to cause the drum beater to
strike a drum head and said cymbal striker
70 to strike a cymbal, said cymbal striker being
relatively movable in said arm, and a sup-
plemental pedal which when depressed with
the main pedal moves said cymbal striker
75 relatively to said arm to an inoperative po-
sition.

4. A drum and cymbal beater comprising
a supporting frame, a drum beater and a
cymbal striker movably mounted in said
frame, a main pedal for operating said drum
beater and cymbal striker, and controlling
means for said cymbal striker having two
80 positions in which it respectively moves the
cymbal striker into different positions rela-
tively to the cymbal.

5. A drum and cymbal beater, comprising
a pivoted beater arm, a pedal for operating
said arm, a drum beater carried by said arm,
a cymbal striker carried by and movable with
90 said arm, said striker being shiftable on said
arm into and out of striking position, and
means operable by the foot in operating said
pedal for shifting said striker.

In witness whereof, I have hereunto set
95 my hand at Kankakee, Illinois, this 19th
day of April, A. D. one thousand nine hun-
dred and twenty-one.

LAWRENCE A. MUELLER.
